Inventor:

James Martin Fox.

UNITED STATES PATENT OFFICE.

JAMES MARTIN FOX, OF MADISON, WISCONSIN.

LETTER ENVELOPE.

Application filed August 6, 1923. Serial No. 656,145.

To all whom it may concern:

Be it known that I, JAMES MARTIN FOX, a citizen of the United States, residing at 727 West Main Street, Madison, in the ⁵ county of Dane and the State of Wisconsin, have invented certain new and useful Improvements in Letter Envelopes, of which the following is a specification.

This invention relates to letter envelopes ¹⁰ particularly of the "repeater" type.

The object of my invention is to provide an envelope of the "repeater" variety, such as most railways use in their business, which will be lasting and useful for months or ¹⁵ years whereas they now last only for weeks.

To accomplish this object, two horizontal slits of any desired length and of any desired distance apart are inserted at or ²⁰ near the center of the front wall of the envelope; into and through which slits an auxiliary address card of stiff paper or light pasteboard may be inserted; having the body portion of the front wall of the envelope ²⁵ between the slits located behind the reversible address card; thus holding in secure position the auxiliary address card upon which the addresses on each side of the card are to be written. Whenever it is ³⁰

desired to use a new and different address a new address card may be used on which to write it and the card inserted through the slits adapted to receive said card as described.

The length of the auxiliary address card ³⁵ will be about the same as the width of the envelope and the width of the card about the same as the length of the slits in the front wall of the envelope adapted to receive the address card.

It will be readily understood that by this device a "repeater" envelope will be provided which may pass back and forth between the parties and destinations shown ⁴⁵ on the reversible sides of the auxiliary address card repeatedly for a very long duration of time instead of being consigned to the waste basket after being used about a dozen times only or until the last blank space provided for the address has been filled.

The advantages and usefulness of my device will be further made clear to the understanding by the following detailed description and the drawings with reference ⁵⁵

numerals, which become a part of this specification and in which—

Figure 1 is a front view of the envelope with the address card in position and exposing one address to view. ⁶⁰

Figure 2 is a front view of the envelope without the address card. Figure 3 shows one side of the reversible address card.

Fig. 4 is a sectional view on the line 4—4 of Fig. 1. ⁶⁵

The application of my device is made by inserting the reversible auxiliary address card 5, inside the front wall 1, of the envelope, down through the top slit 2, over and across the strap 3, thence inside the envelope again through the lower slit 2, and down until said address card 5, lodges at the lower inside edge 4, of the envelope. In this position the lower end and the upper end of the address card 5, are located ⁷⁰ against the inside edges 4, of the envelope and that with the additional security provided by the strap 3, prevents said address card 5, from becoming dislodged until withdrawn for the purpose of reversing the sides ⁷⁵ or ends of said auxiliary address card 5, to show a different address between the slits 2, over the strap 3.

What I claim as a new and useful improvement is:

1. The combination of an envelope having a pair of slits forming a strap, with an address card adapted to bear different addresses on different portions thereof, said card adapted to be inserted into said envelope and over the strap to selectively expose an address-bearing portion on the outside of the envelope, the length of card being equal to the width of the envelope whereby the card is held in position. ⁹⁰

2. The combination of an envelope having two slits parallel to each other and to two opposite edges of the envelope with an address card adapted to bear different addresses thereon on different portions thereof, said card adapted to be inserted in said envelope and through said slits with an address-bearing portion selectively exposed to view on the outside of the envelope between said slits, the length of the card being approximately equal to the width of the envelope so that the card is held in position by the said opposite edges of the envelope. ¹⁰⁰

To which I sign my name.

JAMES MARTIN FOX.
